UNITED STATES PATENT OFFICE

2,337,035

TELEGRAPHIC SYSTEM AND APPARATUS

August D. Eitzen, Rockville Centre, N. Y.

Application May 24, 1938, Serial No. 209,641

23 Claims. (Cl. 40—53)

The present invention relates to apparatus for making manifest information or news which it is desired to impart, and which is especially adapted to receive and exhibit news or information transmitted over a telegraphic system, although it is capable of other uses.

In the well known printing telegraph or ticker system of receiving and manifesting stock quotations and the like or other news or messages, a printing wheel, controlled in accordance with the transmitted telegraphic code, prints upon a sheet or tape of paper which can be viewed by those interested upon directing their attention to it. It will be apparent, however, that the number of persons who can directly view the sheet or tape is limited. It has been attempted to convey the information of the notations on the paper sheet or tape to a larger number of persons by light projecting the images of such notations upon a screen or wall, the images being enlarged if desired.

The projection method has, however, limitations and disadvantages of which may be mentioned that only about five inches of tape can be enlarged in the usual sized office. If space permits, the practice has been to still further magnify the five inches of tape at the expense of the light intensity. The legality of the printed characters diminishes as they are enlarged by projection due to a "washing out" of the pigment on the tape. This loss of contrast or visibility almost entirely offsets the advantages of further enlargement. It is also required that the projectors be located in semi-darkened rooms. As for well-known reasons a light projected image is not suitable for use in strongly lighted offices. The utility of the projectors is also very much impaired by the tempermental of the special light transmitting tapes and the variations and pollution of the inks used on the "ticker." These materials become antagonistic to one another under certain weather conditions. The result is an unsatisfactory copy. In humid weather the ink runs together and drips from the type wheel (which also is an objection to the usual "ticker" tape which is directly observed). In dry, hot weather the printed characters may hardly be visible at all (this also is an objection to the directly observed "ticker" tape). These short comings are, of course, very much amplified in the projected image on the screen. The ordinary paper tape is not sensitive to the weather and even though the ink may vary it is still possible to see the printing. The tape is of a highly absorbent nature, whereas the light

transmitting tape is highly glazed and not easily penetrated by the ink. The amount of light available is also limited by that obtained from the filament of an incandescent lamp. There is also a definite eye strain attendant upon the projection method. This is caused by the glare of the light and by the twitching of the image in its movement on the screen. Many attempts have been made to diminish the twitching of the tape at the projector aperture or window, but some irregularities always remain and are then magnified on the projection screen.

It is the main object of the present invention to provide apparatus of the character as indicated which shall avoid the disadvantages as indicated and provide an efficient and accurate machine to accomplish the results as referred to.

Another object of the invention is to provide an intelligence disseminating device operated directly from and forming a part of a telegraph system, for large group observation.

A further object of the invention is to provide a telegraphic code translator receiver to interpret code signals in a legible manner without the use of recording tape, ink or the printing function, thus making unnecessary the constant service of taping and inking a printer.

A further object of the invention is to provide a means for receiving telegraphic messages, suitable for group observation, of unlimited length and size.

A further object of the invention is to provide devices for the reception of telegraphic messages, which in turn are legibly interpreted in a size readable from considerable distances without the use of an enlarging projector or any optical system, operated at a speed equivalent to a transmission speed.

A further object of the invention is to provide a telegraphic receiving instrument that translates a received message in duplicate, quadruplicate or any multiple thereof from a single incoming pair of wires or single telegraph line, to be read simultaneously in different rooms in the same office or building and each bearing the same message or legend and also using a single machine if desired.

A further object of the invention is to provide a device having prepared characters stored in magazines so that a readable message can be assembled in response to telegraphic impulse codes upon a suitable conveyor such as a belt for the purpose of transporting the message into an observation area to be read, the prepared characters after having passed the observation area

being lifted from the conveyor and transported through a sorting device and returned to their proper magazine for repeated use in the forming of messages. The prepared characters may be of a suitably large size and of a maximum contrast, such as black on white or white on black. The more pronounced the contrast of the characters with their backgrounds, the easier the message can be read at a distance with a minimum enlargement.

A further object of the invention is a method of forming messages from telegraphic impulses in a novel manner which may be described as follows:

The effects of the received electrical impulses are stored in a pin storage disk after a selection and transfer operation by a distributor, thus forming a mechanical equivalent of the character codes sent. The following code characters sent are received and transferred to the storage disk in their proper sequence. The storage disk is geared to and moves with the same angular velocity as the conveyor belt and the instant the character has been transferred and while both disk and belt are in motion a definite character space has been reserved on the conveyor belt. When this reserved space arrives at a point, in its travel, where the corresponding mechanically stored character is the same as the character in the magazine at this point, an electro-magnetic trigger instantly causes the proper character to be placed in its proper position upon the belt. This method provides a plurality of transfer points operating in complete independence of each other. This is in contradistinction to a printing telegraph where all desired characters to be printed must first be brought in line with a single transfer point, or printing position, to be applied to an intelligence bearing medium, such as paper tape. Obviously a typewheel to produce characters of large dimensions would be so heavy and ponderous that fast transmission would be impossible to say nothing of the tape expense necessary to the printing of large characters.

A further object of the invention is to provide a machine for the display of telegraphic messages of a size to be viewed by a large audience, such as the display of stock exchange quotations, which will require a minimum of service attention over long periods of time. The present method for such large sized displays, namely the projected tape method, requires a man to service the "ticker" and also a man to service the projector. This divided responsibility does not always work to the advantage of the user of the machines. In actual practice there have even been instances of sabotage of one man against another or of a state of complete indifference on the part of one of the service men, resulting in poor service to the users of the apparatus. The nature and features of the present invention are such that this constant attention is not required. One man only is needed to service the machine and then only at long intervals and not during business hours, which is of great advantage, and the fact that only one man is required fixes the responsibility for any defective service.

A further object of the invention is to provide a means in combination with a printing telegraph of either a "step-by-step" or permutation type printing telegraphic receiver, to apply the received impulses simultaneously upon the belt co-ordinated message storage disk, while printing the usual record copy on paper tape. This provides open exhibition of the communication to a

large number of persons and at the same time produces a record copy for record purposes. An additional advantage resides in the fact that increased and diversified exhibition of the messages is secured with no increase in the telegraphic circuits required whereby a substantial money saving is realized.

A further object of the invention is to provide a device which, although it may form no part whatever of a telegraphic system will convert characters on a tape or other medium to code signals such as those of the "Baudot" code and impress them upon a conveyor co-ordinated storage disk, for the purpose of producing messages in large sized type to be read by large crowds. This device is capable of discerning the identity of characters presented to it and of sending a predetermined selected code corresponding to each such character. This device can also be used to perforate a tape to be used to re-transmit telegraphic messages on individual or local telegraph distribution systems.

A further object of the invention is to provide improved methods for displaying information or messages.

Other and ancillary objects of the invention will appear hereinafter.

In the accompanying drawings which illustrate the invention—

Fig. 1 is a top plan view of the machine, the casing being shown in section and certain of the parts being broken away;

Fig. 2 is a side elevation of the apparatus of Fig. 1;

Fig. 1a is similar to Fig. 1, but on an enlarged scale, showing more in detail the apparatus at one end of the device;

Fig. 2a is a side elevation of the apparatus of Fig. 1a being a similar view to Fig. 2;

Fig. 3 is a top plan view in linear development of a row of character plate magazines, partly broken away to show a section through the means for assorting the character plates and directing them into their proper magazines;

Fig. 4 is a side elevation of the apparatus of Fig. 3 showing the character plate assorting means;

Fig. 5 is an end view, partly broken away, of the magazines for the character plates and the assorting means therefor;

Fig. 6 is a perspective view, partly broken away to show the means for moving the character plates removed from the display belt along the magazines and assorting them so that each will be guided into its proper magazine;

Fig. 7 is a fragmentary view, taken at a section transversely of the retriever belt showing the relation of the retriever belt to a character plate moved by it;

Fig. 8 is a perspective view of a character plate;

Fig. 9 is a perspective view of a modified form of character plate;

Fig. 10 is an elevational view of a character plate magazine, viewed from the front, that is, the end adjacent the display belt;

Fig. 11 is a fragmentary view in side elevation of the plate release, control magnet and connected levers;

Fig. 12 is a top plan view of a character plate magazine;

Fig. 13 is an enlarged fragmentary view, taken across the operating belt for the character plate transferring mechanism;

Fig. 14 is a side elevation of the character plate magazine shown in Fig. 12;

Fig. 14a is a fragmentary view, in perspective, of the means for guiding the claw plates for moving the character plates forward;

Fig. 15 is a bottom plan view of the character plate magazine as shown in Figs. 12 and 14;

Fig. 16 is a section on the line 16—16 of Fig. 14;

Fig. 17 is a section on the line 17—17 of Fig. 16;

Fig. 18 is a section on the line 18—18 of Fig. 17;

Fig. 19 is a side elevation, largely diagrammatic, of the display belt and its operating means;

Fig. 20 is a top plan view, largely in diagram, of the belt for operating the magazine mechanism and its operating means;

Fig. 21 is a side elevation of the apparatus of Fig. 20;

Fig. 22 is an enlarged fragmentary view showing in side elevation the means for operating the magazine mechanism by the operating belt;

Fig. 23 is an enlarged top plan view, partly broken away, of the mechanism for controlling and operating the sets of pins controlling the application of the character plates to the display belt;

Fig. 24 is an enlarged section, partly broken away, on the line 24—24 of Fig. 23;

Fig. 25 is a development of a section taken on the line 25—25 of Fig. 23;

Fig. 25a is a fragmentary view showing the manner of operation of the bail for depressing the pins;

Fig. 25b is a fragmentary view showing the manner of operation of the bail for restoring the selector magnets;

Fig. 26 is a section, on an enlarged scale, on the line 26—26 of Fig. 23, showing one combination of circuit closing balls and pins where the circuit is closed to energize a magazine control magnet and release one of the characters against the display belt;

Figs. 27 and 28 are views similar to Fig. 26 showing different combinations of pins and balls with which the circuit of the magazine control magnet is open;

Fig. 29 is a fragmentary view, on an enlarged scale, showing the contacts controlling the shift of control from one set of character magazines (as letters) to the other set of characters (as numerals);

Fig. 30 is a diagram showing thirty-two different combinations of the flat-sided or round balls for the character magazines, this providing for the use of thirty-two characters;

Fig. 31 is a diagram showing circuits and apparatus for controlling the character plate magazines and related apparatus;

Fig. 32 is a diagram showing the manner of connecting a plurality of sets of display belts, character magazines, etc., for operation from one controlling means;

Fig. 33 is a fragmentary elevational view showing a modified construction for adjusting the controlling pins;

Fig. 34 is a diagram showing a modification whereby the display devices are operated from the usual printing telegraph "ticker";

Fig. 35 is a diagram showing a modification wherein the display apparatus is controlled by photo-electric cells acted upon by printed "ticker" tape;

Fig. 36 is a section on the line 36—36 through the photo-electric device of Fig. 35, on an enlarged scale;

Fig. 37 is a diagrammatic elevational view showing the relation of concentrated source of light

to the measuring apertures for the photo-electric cells and a "ticker" of which the printed tape is the light controlling means;

Fig. 38 is a graph showing the effect in the apparatus of Fig. 35, of the "bucking" coils on the light controlled coils;

Fig. 39 is an end elevation of a centrifugal motor-control as employed with the driving motors of Fig. 31;

Fig. 40 is a side elevation of the device of Fig. 39;

Fig. 41 is a view similar to Figs. 26, 27 and 28 but with a row of balls between rows of pins and therefor unacted on by pins;

Figs. 42 and 43 are fragmentary enlarged views showing the relationship of characters printed on the tape to the light measuring windows of the photo-electric cells.

Referring to the drawings, and first to Figs. 1 to 32, inclusive, 39, 40 and 41, the apparatus comprises an endless steel belt 116 operating as a conveyor for character plates, that is, plates carrying desired characters (see Figs. 8 and 9) which are attached to the belt by magnetism. These plates are adapted to be applied to the belt in two rows, the upper row being letters and the lower row being numerals, after the manner of the usual "ticker" tape. At each end of the belt are two circular rows of magazines. In the lower row there is a magazine for each one of the numerals employed, all of the numerals of one kind being in a magazine, and in the upper row of magazines there are as many as the letters employed (together with the punctuation marks or other symbols). All symbols of one kind, as for instance a letter, are in one magazine.

The character bearing plates are selectively projected from the magazines upon the belt to which they are secured by magnetic attraction, so as to form the desired notations indicated on the belt as illustrated in Fig. 2. This operation occurring at both ends of the belt, the notations pass, upon one course of the belt, from left to right, and on the other course, from right to left. The same notations may be placed on both of the courses so that the message may be viewed from both sides of the apparatus. The character plates placed on the belt at one end of a course are removed from that course adjacent the opposite end of the belt and pass through an assorting device whereby each character plate is assigned to its appropriate magazine at that end of the belt, in readiness to be again projected from the magazine in its turn in response to the telegraphic code signals received. This operation takes place in relation to both the letter characters and the numeral characters. The mechanism is housed in a casing A which may have a soundproof lining B to prevent any sound of operation of the machine from emanating to any annoying extent, and in the sides of the casing are provided the windows C and D through which the notations on the belt may be viewed, as this belt carries the characters past the windows, such windows being preferably closed by glass or other suitable transparent material, or left open.

In the apparatus shown the telegraphic message is received from the distant station in the well known "Baudot" code, such as is used at present for operating the usual stock quotation "tickers." According to this code a signal element (corresponding to a character, such as a letter or numeral) consists in a predetermined time interval divided into a number of periods

(usually eight) and each signal is distinctively represented by a permutation of plus and/or minus impulses during said interval, there being only one impulse in one of said periods and the number, and relative polarities of the impulses depending upon those required to represent the signal according to the code.

The apparatus may now be referred to in detail as follows:

The code messages consisting of plus and/or minus impulses as stated come in from the transmitting station over the line 1 and pass through the polarized relay 2 to ground at 3 (see particularly Figs. 24, 25 and 31). When the appropriate polarity of electric impulse passes through the magnet 2 the pivoted contact arm 4 is moved from against its back contact into contact with the forward contact 5. Circuit is then made from the ground at 6 through the battery 7, relay contacts 4 and 5 and the conductor 8 to the distributor for suitably distributing the electric impulses of the transmitted character to the selector magnets for creating the proper selective setup to select the desired character for application to the display carrier. The distributor comprises the central circular contact piece 9 and the several contacts 10 to 17 inclusive, arranged concentric about the contact 9. Concentrically journaled with these contacts is the rotating contact arm 18 carrying the brushes 19 and 20 engaging respectively with the contact 9 and the several contacts 10 to 17 inclusive, as the arm is rotated.

These contacts 10 to 17 inclusive, eight in number, corresponding to the usual Baudot code employed for operating "tickers" wherein the time interval corresponding to a signal is divided into eight periods, an impulse in the first period operating to start the distributor and an impulse in the last period serving to stop the distributor arm, the impulses in the intervening periods indicating the code signals. In the present case the period devoted to stopping the distributor is unnecessary and consequently the contact 16 is idle, that is unconnected.

The distributor arm 18 is driven by a frictional drive from the motor 46, and the arm 18 is held in its initial position by a pivoted dog 21 spring-pressed into holding position and moved out of that position by the attraction of the electro-magnet 22.

When the arm 18 is in its initial position and the line impulse closes the relay contacts 4 and 5, circuit will be completed from ground at 6 through the contact 9, arm 18, brushes 19 and 20 to segment 17 and conductor 23 through magnet 22 to ground at 23'. This also operates to energize the magnet 204 whereby the controlling arm for the motor 46 is restored to its initial position as will be hereinafter referred to, and also energizes the electro-magnet 205 whereby the controlling arm 238 for the motor 172 for driving the display carrier or belt, is controlled as will be hereinafter referred to.

When the arm 18 is released from its initial position by the raising of the dog 21 as described, the arm 18 will be turned by the motor 46 and the contacts 10 to 14 inclusive, of the distributor, will be successively connected through the conductors 24, 25, 26, 27 and 28 with the magnets 30 to 34 (see Fig. 31) respectively, for selectively setting the pins according to the received code character, for selecting the proper symbol to be displayed, the circuits of these magnets being respectively completed from the conductors as

indicated through the ground at 35. The contact segment 15 is connected by the conductor 29 with the electromagnet 36 which is the "shift" magnet for determining whether the character to be projected upon the display belt is to come from a magazine in the upper or "letter" row or the lower or "numeral" row.

It will be seen that as the arm 18 rotates, in one revolution it will, on leaving the starting 10 contact 17, successively engage the contacts 10, 11, 12, 13 and 14, and the energization of the magnets 30, 31, 32, 33 and 34 will depend upon whether or not an impulse is being received over the line 8 at the time the arm 18 is in contact with any particular one of the contacts 10 to 14 inclusive. In other words, the magnets will be energized according to whether or not an impulse is received over the line 8 at the time the distributor arm 18 is in contact with the contact segment to which the magnet is connected, and accordingly the magnets energized will depend upon the number and arrangement of the impulses. The same set up of the magnets 30 to 34 corresponds to a letter in an upper row of 20 magazines and a numeral in a lower row of magazines, the letter or numeral being selected according to whether or not the so-called "shift" magnet 36 is energized, this depending upon whether an impulse comes over the line 8 when the distributor arm 18 is upon the contact segment 15.

The circuit connections and mechanism operated by the magnets 30 to 34 respectively are similar and therefore are shown (see Fig. 25) in connection with one of the magnets (30) only. It will be observed that the condenser 37 is connected in parallel with the magnet 30 to insure operative energization of the magnet and reduce or prevent arcing at the distributor contacts 35 on breaking the circuit which might be injurious due to the inductive discharge of the magnet. The magnet 30 has an armature 38 pivoted at 39 and at its lower end has pivoted a member 40 sliding in the guide 41. The impulse through the 40 magnet 30 causes the member 40 to be moved endwise over the head at the top of the plunger 42 after which the member 43 is caused to move downward by the cam 44 (Figs. 24, 25 and 25a) on the shaft 45 upon which the distributor arm 50 18 is fixed and which is driven from the motor 46 through the friction clutch 47 by the gear 48 meshing with the gear 49 on the motor shaft.

The member 40 having been projected over the plunger 42 and between the plunger and the member 43, when the member 43 is forced downwardly it will, through member 40, force the plunger 42 downwardly until the latch 50 pressed by the spring 51 will engage over the head on the member 42 and hold it in depressed position. 60 If there is no impulse through the magnet 30 the member 40 will remain in the position as shown, so that when the member 43 is depressed as stated it will not operate to depress the plunger 42. The bail 43 extends along the entire row of magnets 30 to 36 inclusive over the plungers 42 of which there is one corresponding to each of the magnets, but the descending bail 43 will only depress those plungers of the row which have their corresponding magnets energized as described. A spring 40' corresponding to each of the members 40 supports such member in its elevated position while a spring 42' for each of the plungers 42, supports the plunger in elevated position.

70 There is also a pair of contacts 67 for the

radial row of plungers 42 which is closed when any of the plungers is depressed and open when all the plungers are elevated for a purpose as will hereinafter appear. When any of the springs 42' is depressed by the depression of its plunger 42, the bars 67, which extends beneath all the springs' of a radial row, will be depressed thus closing the contacts 67 as stated.

Carried in the rotating storage disk 52 (Figs. 23 to 28 inclusive and 41 are the radial rows of pins 53 slidably mounted in the disk. A number of pins in a radial row is equal in number to the number of plungers 42 in a radial row, which number corresponds with the number of selector and "shift" magnets as before described.

Beneath the disk, and extending entirely around it, is the stationary plate or disk 54 having for each circumferential row of pins 53 two channels 55 and 56 each adapted to receive the circular, double-wedged-shape in cross section, heads of the pins 53. These channels are one above the other and extend entirely about the circumference except as will now be noted. The channels end at the wall 57 (Figs. 23 and 25) of a recess 58 against the bottom of which all the pins come on emerging from the channels 55 and 56. The pin heads then all travel up the inclined or cam surface 59 to a level where they are in line with the upper channels 55 and travel therein until a recess 60 in the stationary plate is reached.

If a plunger 42 is not depressed the pin 53 passing thereunder will be supported by a spring 61 in passing the recess 60 so that the pin head will pass on into the upper channel 55. If, however, the plunger 42 is depressed, then the pin 53 on attempting to pass it will be cammed downwardly depressing the spring 61 and causing the head of the pin to enter into the lower channel 56. The pin has now been set for proceeding in depressed position in its travel to complete a revolution until it comes to the ends of the channels as stated. As a depressed pin 53 enters the channel 56 the head of the pin 53 will depress the spring contact arm 62 into contact with the spring contact 63 whereby a circuit will be completed from ground at 64 through the battery 65, contacts 62 and 63, conductor 66, contacts 67 and electro-magnet 68 to ground at 69.

It will be seen that this circuit of the magnet 68 is dependent upon both a pin 53 and its corresponding plunger 42 being depressed, the former being necessary to close the contacts 62 and 63 and the latter to close the contacts 67. This wipes out each code set-up in the plungers 42 immediately after it has been transferred to a radial row of pins 53 in the rotating disk. This prevents the duplication of the code by instantly retracting the plungers 42 under the action of the springs 42'. It will be observed that the magnet 68 is energized as a radial row of pins 53 passes the recess 60, or transfer point, when the latches for holding the plungers 42 in code transfer position will be released and the plungers restored for the next incoming code character. The energization of the magnet 68 effects this restoration and wiping out of the code set-up by attracting its armature 70 pivoted at 71 against the tension of the spring 72, thereby drawing the arm 73, which is pivoted to the arm 70 at 74, to the left (see Fig. 25.) This movement of the arm 73 causes a like movement of the bar 75 attached thereto, this bar 75 extending along the entire row of plungers 42. The bar 75 will, therefore, come against the tips of the latches 50 cor-

responding to the plungers, which will be withdrawn thereby against the springs 51 and unlatch the plungers 42 which then spring upwardly under the actions of the springs 42'. This restoration of the plungers 42 will occur after a radial row of pins 53 in the rotating disk has passed the recess 60 and the pins have entered their corresponding channels in the disk 54, and conforming to a desired code character, for a revolution of the disk. The entire row of plungers 42 will thus be set in position for actuation by the following code character selected by the magnets as described.

10 The member 40 for each of the plungers 42 will be simultaneously reset to position to be operated for a new set up by the code energized magnets, by reason of the cam 44' upon the shaft 45 drawing the ball 76 against the tails of all the magnet armatures 38 (see Figs. 25 and 25b.) This takes place just as arm 18 has passed beyond contact 15 on the distributor.

15 It will now be seen that each radial row of pins 53 will in its turn, be set by the impulses corresponding to a code character operating through the electro-magnets 39 to 36 inclusive, being in elevated or depressed positions respectively according to whether they have been entered within the upper channel 55 or the lower channel 56 according to the impulses of the code character.

20 In order to select a character to be exhibited, such as a letter or a numeral, the pins of a radial row are respectively elevated or depressed to form a combination adapted to select the desired character to be exhibited. In order to accomplish this selection of the desired character according to the set up of the radial pins of a radial row as described, there is arranged a series of selector contact combinations beneath which pass all the code set-up radial rows of pins. There is a contact operating combination corresponding to each one of the characters to be exhibited.

25 When a code set-up of a radial row of pins 53 in the rotating disk 52, corresponding to a certain character, passes beneath the selector contact combination corresponding to that character, that selector contact combination will be operated to actuate the means for exhibiting the corresponding character, and this contact combination will be operated only by the corresponding code set up of a radial row of pins, such code set up of pins having no effect upon the other contact combination beneath which it passes, which contact combinations correspond with other characters or symbols to be selected for exhibition and are effectively actuated by their own code set ups of radial pins 53. There is a plurality of these selector contact combinations, one for each of the characters (as letters) in the upper row of magazines and for the respectively corresponding characters (as numerals) in the lower row of magazines. Whether the upper or lower magazine character is released depends upon the position of the "shift" contacts forming a part of the combination as will be hereinafter referred to. Also the same selector contact combination simultaneously controls the characters at the other end of the display belt. These selector contact combinations are stationary with relation to the disk 52 and are distributed thereabout (see Fig. 31) being equally angularly spaced as shown by the positions *a*, *b*, these combinations being similarly spaced around to the position *c*, the intervening positions of the combination not being shown for the sake of clearness.

Each of the contact combinations controls its character magazines in the same manner so that a description of the combination *a* will serve to illustrate each of them.

Thus referring to Figs. 26, 27, 28 and 41, as well as Fig. 31, the contacts 77 are in a circuit controlling the connection with the character magazines corresponding with that particular row of contact combinations. These contacts are opened or closed according to the relative positions of the full balls 78 and 79 and the flat-sided balls 80, 81 and 82. These balls 78 to 82 inclusive are mounted by suspension bars 83, 84, 85, 86 and 87 respectively, to swing universally from the universal suspensions 88, 89, 90, 91 and 92 respectively, the balls being pressed downwardly by means of springs as 92' (see Fig. 25). In the position as shown in Fig. 26, the balls 78 to 82 inclusive are in line, so that the distance from the stationary plate 93' against which the end of the ball series abuts, to the contacts 77 is a maximum and the contacts 77 are pushed into a closed position thereby causing the ejection from its magazine of the proper character as will be hereinafter referred to.

It will be seen that the relative locations of the balls 78 to 82 inclusive is occasioned by the code set-up of the radial row of pins 53 cooperating therewith, in the case illustrated the inner two pins being depressed into the lower channel 56 in the member 54, while the other three pins are elevated, their heads being in the upper channels 55. This relative positioning of the pins 53 holds the balls in line as shown so as to close the contact 77. The combination of full balls and flat-sided balls, as shown in Fig. 26, will only be effected by this particular code set up of pins. For other set ups of pins the balls and half-balls of this row will be thrown out of line so that the over-all distance from one end of the row of balls (the plate 93) to the other will be lessened so that the spring contacts 77 will spring open and there will be no operation to release a character at this contact station. Thus, for instance, in Fig. 27, the code set up of pins is not such as to push the contacts 77 together. It will be seen that the two inner pins are one depressed and the other raised instead of both being depressed as in Fig. 26, and consequently the balls are thrown out of line and the contacts 77 remain open.

Also in Fig. 28 the combination is not such as to close the contacts 77 because one of the pins operating on one of the flat-sided balls is depressed instead of all three of the pins for operating the flat-sided balls being elevated as in Fig. 26. When the balls are not acted upon by any pins, as when they are between radial rows of pins, they will be pressed downwardly against the disk 52 when the center lines of the balls will lie below the contacts 77 so that those contacts will not be pushed together (see Fig. 41).

At the outer end of each radial row of pins 53 is another pin 93 which, when elevated, closes the contact for the release or ejection of a character, namely a letter, of the upper row of magazines on the display device, and when the pin 93 is depressed contact is made to release or eject a character, namely a number, from the lower row of character magazines. The different combinations of full and flat-sided balls to correspond to different code set ups of the pin to select the desired characters, are shown in Fig. 30 with the contacts at the right hand side for selecting the upper or lower row of characters, which last is

equivalent to the shift which is occasioned by the shift pulse in the tickers commonly now in use. The manner of selection of the character to be ejected from the display device is accomplished as follows, referring particularly to Fig. 31:

From the ground at 94 circuit passes through the battery 95, the master contacts 96 and the conductor 97 to the conductor 98 to which one side of each of the pairs of contacts 77 of the contact combination stations (radial rows of balls) is connected. When the pair of contacts 77 is closed, for instance at the contact combination station *a*, circuit is closed thereby from the conductor 98 through the conductor 98' to the middle contact 99 of the "shift" contacts for selecting the upper or lower row of characters as before referred to. The others of the "shift" contacts are the contact 100', on one side of the middle contact, and the contact 105', these contacts 99, 100' and 105' constituting the "shift" contact (see Fig. 29). The contact 99 is a spring contact and is biased to normally stand in engagement with the contact 105'. When, however, an elevated pin 93 comes in contact with the lateral, insulated arm 103' on the contact 99 and raises the same, the contact 99 will be moved into engagement with the contact 100'. This condition is shown at the left hand of Fig. 29. The next set of contacts in Fig. 29 shows the pin in depressed position and out of engagement with the contact arm, so that the central contact is in its normal position of engagement with the contact 105'. Whether or not, therefore, an upper or lower magazine character is selected depends upon whether or not the pin 93 under the arm 103 at the time is depressed or elevated.

Assuming the "shift" pin 93 to be elevated at the contact combination station *a*, circuit will be continued from the contacts 77 through the conductor 98', contacts 99 and 100' to conductor 100 and 101, thence through magnet 102 corresponding to the "A" magazine to conductor 103 and to ground at 104. The magnet 102 for the particular character selected (letter A) will thus be energized and the character will be released to be projected upon the display belt. This "A" magazine and its magnet 102 are one of the row 110 of similar magazines, there being a sufficient number to provide for all of such characters, only the first two of the row and the last being shown, the others being omitted to avoid complication. Each of the magazines and its character release magnet is operated in the same way from its appropriate contacts 77 according to a suitable pin set up so that the manner of operation of one of the magazines with its release magnet is illustrative of all of them in the row.

Also with the contacts 77 closed and the "shift" contacts 99 and 100' being in contact as described, circuit may also be traced from the conductor 100 through the magnet 102' controlling the character release in the "A" magazine of the row 110' at the other end of the display belt, to the ground at 104'. The release of the A characters will, therefore occur simultaneously at both ends of the display belt, and similarly the B characters will be simultaneously released, and similarly the C characters and so on.

If the "shift" pin 93, however, is depressed, and the contacts 99 and 105' are in engagement, the contact 100' being then disengaged, circuit may be traced from the closed contacts 77 through the conductor 98' contacts 99 and 105' and the conductors 105 and 106 through the character

release magnet 107 of the end magazine (the numeral 1) in the lower row 111 of magazines at one end of the belt, the circuit proceeding from the magnet 107 to conductor 108 and to the ground at 109. The number of magazines, each with its release magnet, in the row 111 is sufficient to provide the number of desired numeral and associated characters, each magazine and its magnet operating in the same way from its appropriate contact combination station under the influence of the appropriate set up of pins in the rotary disk, therefore the description of the operation of the "7" magazine is illustrative of the operation of each of the magazines.

Also from the conductor 105 circuit may be 15 traced through the character release magnet 107' of the "7" magazine of the lower row of magazines 111' at the other end of the display belt, the circuit being completed from the magnet 107' to the ground at 109'. The release magnets of 20 the "7" magazines at both ends of the display belt will thus be simultaneously operated to release their numerals to be displayed on opposite sides of the display belt.

Similarly the contact combinations and "shift" 25 contacts at the station *b* will operate in the same manner to simultaneously release characters from the B magazines of the upper row at opposite ends of the display belt, when the "shift" contacts are in one position and to release the characters from the "two" magazines of the lower rows at both ends of the display belt when the "shift" contacts are in the other position, and similarly the 30 contact combinations of each of the stations will operate upon its appropriate letter magazines and numeral magazines at the two ends of the display belt.

All pairs of conductors as 100 and 105 from 35 contact combinations station *a*, conductors from station *b* and so on connect to terminals in a contact plate 600 from which such conductors can be extended to any number of display devices, one after the other, located in any convenient situations. Thus the display mechanism having the casing A' and window D' may be connected with the wires at contact plate 600 by a cable 601 having suitable wires plugged into the wire terminals in the contact plate 600 in the master machine in casing A having a window D. Similarly the wires may be extended from the display device just referred to, to the display device having the casing A'' and window D'', by means of a cable 602 having suitable wires, similarly the wires may be extended through a cable 603 to a display device having the casing A''', and the windows C''' and D''', and so on indefinitely. In this way any desired number of display devices may be operated from one controlling means. The wire 604 connected with a terminal in the contact plate 600 and also with ground at 905 is connected through all the cables and display devices and supplies a ground connection back to battery 95 to complete the circuits from each display device.

As before referred to the magazines for the various characters are arranged in two rows 110 and 111, at one end of the display belt, the upper row having the letters and the lower having the numerals, and similarly two rows of magazines 110' and 111' are arranged at the other end of the display belt (see Figs. 1, 1a, 2, 2a, 20 and 21). The character members comprise characters carried (see Figs. 8 and 9) on plates as 112 having the character 113 on one face and upon the op-

posite side having the permanent magnets 114 and 115.

5 The character bearing plate 112, when ejected from its magazine has its permanent magnets 114 and 115 pulled against the flexible steel display belt 116 so that it adheres thereto and is carried along thereby. The magnets 114 and 115 are hollowed out at 114' and 115' so that they contact with the belt at their ends. Clearance is thus provided permitting the belt to flex about its pulleys without interfering with the attachment of the character plates thereto and to get a maximum magnetic pull.

The letter, figure or other character on each plate, and the plate forming a background therefor are preferably contrastingly colored as, for instance, the character being black and the remainder of the plate being white; also the display belt should be colored the same as the character background of the plate otherwise those portions of the belt visible between the character plates would break up the character background of the display and might even produce apparent notations in the display which are unwanted and may be misleading.

20 Each of the magnets 118 and its operating mechanism for the character plates is precisely the same as every other and a description of one will therefore be a description of each.

Each of the magazines comprises a box 117 which is open at both front and rear and within which the character plates 112 having the same characters are located or stored, one back of the other, and from which the characters are successively ejected one at a time against the display belt by mechanism controlled by the magnet 118.

25 When the magnet 118 of a magazine is energized it attracts its armature 119 against the force of the spring 120 thereby pulling upwardly upon the link 121 which is pivoted to a plate 122 fixed on the rotatable shaft 123 thereby turning the shaft and the gear 124 fixed thereon which meshes with the rack 125 and slides the same to retract the stop or dog 126 from in front of the top of the character plate 112a (see Fig. 17). Also pivoted to the plate 122 is the link 128 which will be drawn upwardly and thereby turn the crank arm 129 to which the link 128 is pivoted. The crank arm 129 is fixed on the shaft 130 as is also the gear 134 meshing with the rack 134' on the sliding stop 131 which, under the turning as stated, acts to withdraw the stop 131 from in front of the bottom of the character plate 112a simultaneously with the withdrawal of the dog 126 from in front of the top of that character plate. This releases the plate 112a which is projected into operative relation to the belt by the quick action of the spring-pressed fingers 219, the plate being then held to the display belt by magnetic attraction as it passes along therewith through the exhibition area.

30 In order that but one character plate may be ejected from the magazine at a time it is necessary to place a restraining means for the plates other than the front one (adjacent the display belt) when the front plate is ejected. This is accomplished by having the two sliding stops 132 and 133 moved inwardly by the gears 124 and 134 to a position in front of the second plate from the front at the time that the dogs 126 and 131 are moved to release the front plate. When the magnet 118 is deenergized the spring 35 120 will replace the parts so that the stops 126

and 131 will again project inwardly so as to stop the front character plate, while the stops 132 and 124 are moved outwardly into the position as shown in Fig. 17, the next plate then advancing into ejection position against the stops 126 and 131.

Along the rear of each row of magazines runs a retriever belt by which character plates detached from the display belt are carried back through an assorting device and each character plate is deposited in its appropriate magazine at the rear of the plates already in the magazine. The rear of the magazine is that side which is opposite the display belt.

To receive the character plates into the magazine from the retriever belt and carry them forward through the magazine to the point where they are successively ejected from the magazine upon the display belt as just described, the following mechanism is provided:

The claw plates 250 slide forward and rearwardly upon the exterior of the sides of the magazine 117 and upon the pins 251 entering the slots 252 in the plates. Springs 251' are interposed between the heads of the pins 251 and the plates 250 so that the plates are yieldingly held against the outer sides of the side walls of the magazine. Inwardly turned on the claw plates are the claws or fingers 253 which extend inwardly of the side walls of the magazine sufficiently, when the claw plates 250 lie against the magazine side walls, to overlap the edges of a character plate 112 to be moved forward in the magazine. These fingers are adapted to pass back of the character plate as it is delivered by the retriever belt and draw the character plate into the magazine for a certain distance. The claw plates 250 slide inwardly sufficient to clear the rear end of the magazine, and during the operation of their forward movement these fingers slide in the slots 254 and 255 in the side walls of the magazine. In sliding forward the claw plates 250 lie flat against the sides of the magazine under the influence of the springs 251' so that the claws or fingers 255 overlap the character plate and draw it in to the extent of the forward stroke of the claw plates 250. On the backward stroke of the claw plates 250 projections 256 and 257 on each of the plates ride up spring inclines as 258 (see Fig. 14a) whereby the fingers 253 are forced outwardly against the springs 251' so as to pass by the edges of the character plate about to be engaged, and when the projections 256 and 257 pass off of the inclines 258 they are forced inwardly by the springs 251' and drop down against the sides of the magazines, the fingers being positioned back of the character plate and in position to draw that plate forward in the magazine to the extent of the forward stroke of the claw plates 250. In this forward stroke the projections 256 and 257 pass beneath the members 258 and 259 so that the fingers 253 are maintained in position back of the character plate during the forward stroke of the claw plates 250. A character plate having been carried forward in the magazine to the extent of the movement of the claw plates 250, it will have been carried past the flexible inclined stops 260 and 261 mounted upon the slides 262 and 263 sliding alternately rearwardly and forwardly in the bottom and top respectively of the magazine. These slides will be at approximately the rearward end of their stroke when the plates 250 are at the forward end of their stroke, so

that the character plate carried by the fingers 253 will be passed to a position in front of the latches 260 and 261 (which yield to permit this) when the claw plates 250 are at the forward ends of their strokes as described. The character plate being thus engaged at its back by the stops 260 and 261 will be carried forward in the magazine as the slides 262 and 263, carrying the stops, move on their forward stroke, the 10 character plate being pushed forward until it comes against the character plate which is the rear one of those previously placed in the magazine, and it will be apparent that the plate being received into the magazine will be moved forward, a greater or less amount according to the number of character plates ahead of it in the magazine.

In order to prevent the falling back of one side of any of the character plates whereby the plate 20 might not stand squarely in the magazine, a number of readily flexible strips or "cat whiskers" 264 are provided in the bottom and top of the magazine, such "cat whiskers" being inclined forwardly so as to resist the movement of a plate 25 edge rearwardly but readily flexible so as to permit the edges of the character plates to pass in a forward direction.

The claw plates 250 are caused to move as described by having each claw plate 250 pivoted to 30 an arm 265, the arms on both of the claw plates being fixed upon a shaft 266 rotatably mounted on the magazine casing. The shaft is biased so that the plates 250 tend to be drawn into their forward positions, by means of a spring 267 secured at one end to a lug 268 formed on the magazine frame and on the other end to a pin 269 fixed in the shaft 266.

The arms 265 are swung rearwardly to push the claw plates 250 rearwardly by means of an 40 arm 270 fixed upon the shaft 266 and having a pin 271 entering within a slot 272 in a strip 273.

It will be seen that the slot 272 provides a lost motion connection so that the claw plates 250 are surely moved fully to the rear end of their 45 stroke but on the forward stroke the slot permits the strip 273 to move forward without the pin 271, the character plates being urged forwardly by the spring 267, the forward movement being limited by coming against the rear one of the 50 series of character plates in the magazine and obviously the position of the claw plates 250 will depend upon the number of plates in the magazine unless the number of plates in the magazine 55 is so small that the claw plates may move forwardly to their limit which is where the ends of the slots 252 come against the pins 251.

The strips 273, moved as described, also actuate the arms 278 which are outside the walls of the magazine casing and have inturned latches 60 279 engaging the back of the character plate which is about to be ejected into operative relation to the display belt. These latches 279 reciprocate rearwardly and forwardly in the slots 280 in the side walls of the magazine. The arms 278 are fixed upon a shaft 281 rotatably mounted upon the magazine frame, which shaft has fixed upon it the crank arm 282 having a pin 283 entering within the slot 284 of the strip 273. The 65 shaft is biased by spring 273' to spring-press the latches 279 forwardly so as to yieldingly project the character plate onto the display belt. The slot 284 is such that upon the forward stroke of the strip 273 the latches 279 will always be 70 moved rearwardly to an extent sufficient so that 75

the latches will engage the next character plate at its back, the latches 279 being flexibly mounted so as to give outwardly to permit the latches to pass the plate. The forward movement of the arms 278 is limited by the stop 278'. Having reached their rearward position the latches spring inwardly back of the plate. On the rearward stroke of the strip 278 the strip can be moved without moving the pin 283, the arms 278 and their carried latches 279 being then pressed forwardly to produce the spring pressure for ejecting the plate, when released, upon the display belt.

The slides 262 and 263 carrying the spring latches 260 and 261 are caused to reciprocate forwardly and rearwardly by the link 285 pivoted at 275 in the clevis 276, having a slot 286 within which enters a pin 287 fixed to arm 288 fixed upon the shaft 289 rotatably mounted on the magazine casing. The clevis 276 is fixed to the belt 277 which is drawn first in one direction and then in the other as will be described.

The arm 288 is also pivoted to a link 290 which is pivoted to the arm 291 secured at one end to the rotatable shaft 292 and having its other end pivoted to one end of the link 293 which has its other end pivoted to the slide 263. The spring 294 fixed to the end of the arm 288 at one end and to the magazine frame at the other, tends to force the slide 263 forwardly. The shafts 289 and 292 extend from top to bottom of the magazine, being rotatably mounted in the frame thereof. At its bottom end the shaft 292 has secured to it the arm 295 which is pivoted to the link 296 which is also pivoted to the slide 262. Also an arm 297 fixed to the rotatable shaft 299, is pivoted at its other end to the link 298, the other end of the link 298 being pivoted to the arm 295. A spring 299 secured at one end to the magazine frame and at its other end to the arm 297 tends to force the slide 262 forwardly. It will be seen that the arrangement of levers for operating the top and bottom slides respectively is the same and that the slides are operated synchronously and in phase inasmuch as their operating levers are connected together by the shafts 289 and 292. It will further be observed that these levers greatly multiply the movements of the slides with relation to their actuating means so that a relatively small forward and rear movement of the link 285 will produce a length of stroke of the slides sufficient to provide their desired range of operation upon the character plates. Also it will be seen that the slides are, at each stroke of the link 285, moved to the rear end of the stroke, but on going forward of the link the pin and slot connection permits the link to move forward while the slides do not necessarily follow but remain spring-pressed against the rear or last one of the character plates in the magazine, the position of the slides depending upon the number of plates in the magazine. The links 274 and 285 will perform two cycles of front and rear movement for each cycle of movement of the clevis 276 and the belt 277 to which it is secured. This is occasioned by the fact that in moving from one extreme position of the stroke to the other the clevis will cause forward and back strokes of the links 274 and 285 and will also cause such forward and back strokes of those links as the clevis moves on its return stroke to its initial position. This doubling of the reciprocations of the links 274 and 285 with relation to that of the belt 277 compensates for an inverse reduction of relative speeds which

takes place in the transmission from the shaft 196 to the belt actuating link 202 (see Fig. 20) so that the reciprocation of the slides 262 and 263, as well as the claw plates 250, is brought into synchronism with the remainder of the apparatus.

The belt 277 is caused to reciprocate as referred to, to effect the foregoing operations, by apparatus as can be clearly seen from Figs. 20 and 21. In the apparatus of those figures, the link 202 is caused to reciprocate from the shaft 196 by means of an eccentric 198 fixed on the shaft exerting alternately a thrust and pull upon the link 200 pivoted to the link 202 at 201.

10 The link 202 is pivoted at one end to the link 300 fixed to a rotatable shaft 302 mounted in the frame, while the other end of the link 300 is pivoted to a link 301, the links 202 and 301 being pivoted to the ends of a link 300' fixed upon the shaft 302' rotatably mounted in the frame at the other end of the apparatus.

15 Fixed to the shaft 302 is a gear 303 meshing with a curved rack 304 fixed to the belt 277 so that as the gear 303 is turned in one direction or the other the belt 277 will be moved first in one direction and then in the other, the belt being maintained arched at all times under the spring tension of springs 305 and 306. At the opposite end of the apparatus a precisely similar arrangement is provided for operating similar reciprocating belts for operating the character plate manipulating means in the magazines at that end of the apparatus. It will be seen that (Fig. 21) each of the shafts 302 and 302' not only operates reciprocating belts as described for the upper or letter magazines at the two ends of the display belt, but also has precisely similar means for operating similar reciprocating belts in connection with the lower or numeral magazines at both ends of the belt.

20 The characters secured to the steel belt by the magnetism as described, having passed through the exhibition stage, are picked off the belt, and returned by a retriever belt to a sorting device where the various characters are sorted according to the location of lugs upon them, so as to be returned to their proper magazines to again be ejected under the control as described so as to be again secured to and exhibited by the belt. The characters, after exhibition, are picked from the steel belt by means of a diverting member 136 (Figs. 1a, 2a, 3, 4 and 6) which diverting member consists of the bent-in ends of the angular rails or guides 137 and 138. The movement of the steel belt causes the character beneath which the ends of the members 136 project to be cammed or lifted away from the belt and carried beneath the rubber retriever belt 139 (which runs along the rears of each row of magazines) and between it and the flanges 140 and 141 on the rails 137 and 138, the character also being between the wider flanges 142 and 143 of such rails. The rubber belt is thus stretched so as to force the character against, and move it along, the rails 137 and 138. These rails conduct the characters removed from the display belt to a sorting mechanism adjacent to and extending along the rear of each row of magazines for the characters, which sorting arrangement permits each character to enter only its own appropriate magazine. Thus each of the characters is provided with a characteristic lug or dog 144 which varies in length along the edge of the character according to the different characters, each character having its own particular

length of lug. This applies to the manner of selection of certain of the characters, other of the characters having a different arrangement of character lugs as will be hereinafter referred to.

In the sorting device the rails 137 and 138 are cut away opposite each magazine as indicated at 145 and 146. Alongside each of said cut-away portions is arranged a flat cam coextensive with the opening in the rail, each such cam having the flat portion 147 and the inclined or camming portion 148. Such flat cam is secured in fixed relation to the rail. Opposite the gap 149 between the flat portions 147 of adjacent flat cams is arranged a pair of character-plate supporting blocks 150 mounted on the magazine support between two adjacent magazines. There is a pair of each of these blocks 150 opposite each pair of gaps 149, for each magazine, in the sorting device. These pairs of blocks have a progressively increasing distance between them and it is this distance which determines the sorting of the characters. The pairs of blocks being arranged so that the distances between blocks of a pair increases preferably from the end at which the characters enter the sorting means, the character plate then having a lug 144 of characteristic length for a given magazine it will, in passing along the sorting device, bridge over the distance between the members of the pairs until it comes to a pair of blocks having a distance between them such that the character lug on the character plate may pass in between the blocks of the pair. This will, of course, occur at the first pair of blocks having a distance between the members big enough to receive the lug.

When the lug passes into the space between a pair of blocks 150, the edge of the character plate will, under the pressure of the elasticity of the rubber belt 139, be thrown toward the magazine and pass beneath the flat portions 147 of the flat cams at both ends of the character plate. The belt then carrying the character plate further onward will cause the depressed edge of the plate to pass through the gaps 145 and 146 into the back end of the magazine, and as the character plate is carried still further its rear or trailing edge will clear the side of the gaps 145 and 146 when the elasticity of the belt will force the plate into a position perpendicular to the sides of the magazine where it can be reached by the claws 253 for advancing it further within the magazine 117 as has been described.

It will be apparent that in this manner the characters will be diverted into their proper magazines according to the length of the character lug 144. The method of sorting the plates as described, however, with the number of characters usually employed (often 30) would require that with character plates of normal size the variations between the different pairs of blocks of the sorting device would have to be extremely small, which would require refinement of workmanship and possibly cause inaccuracy in selection. For this reason some, say half, of the character plates may be selected by means of variation in length of a central character lug 144 as shown for instance in Fig. 9, while the other half of the characters may be selected by means of the variation of the space between two character lugs as 151 and 152 at the ends of the plate as indicated in Fig. 8. With the latter arrangement of lugs, the blocks 153 (Fig. 4) effect the selection. These blocks progressively de-

crease in width and are arranged midway between the rails 137 and 138, a character being selected, or diverted into a magazine, upon encountering the first one of such blocks which will 5 pass through the space between the lugs 151 and 152.

It is apparent that the character plates having the character lugs similar to those in Fig. 8 will not be diverted in passing over any of the blocks 10 150 which are arranged for cooperation with the central character lugs as 144, and will only be diverted into the magazine by encountering the first of the blocks 153 which will pass through the space between the lugs 151 and 152. The arrangement of character lugs as shown in Fig. 8 and selecting blocks for selecting the same is the opposite from the other set of character lugs as shown in Fig. 9 and selecting blocks for the same; in the former case the selector block passing 20 between the character lugs and in the latter case the character lug passing between the selector blocks in diverting or selecting a character plate.

The retriever belt 139 is of suitable elastic material, preferably rubber, is endless and is trapezoidal in cross section. The belt passes about the grooved pulleys 154, 155, 156 and 157, power being applied to one of the pulleys, for instance the pulley 157, to drive the belt 139; the pulleys 163 and 164 are simply idlers for properly directing the belt. The pulley 165 is also an idler and is for the purpose of bearing upon the retriever belt 139 to press it firmly in tractive contact with the driving pulley 157. The belt is supported adjacent the magazine by pairs of beveled 30 pulleys 158, 159, 160, 161 and 162, see particularly Fig. 7 for the arrangement of the pulleys of a pair in relation to the belt, and the relation to the belt of a character plate operated upon by the belt.

40 It will be seen that by reason of the trapezoidal shape of the belt and the beveling of the cooperating pulleys, the belt which tends to occupy the position as shown in dotted lines, is forced into the inner (full line) position by the character plate, and when in such position is clear of the pulleys so that it may give in any direction to permit the character plate to float or adjust itself to any of the devices through which it passes.

45 The retriever belt 139 should preferably be run at a slightly higher linear velocity than that of the display belt 116 so that the character plates taken from the display belt will be certainly disposed of without danger of piling them on the retriever belt faster than it transports them away.

50 It should be understood that there are two rows of magazine at both ends of the belt 116, one row being for letter plates and the other for number plates, the letters being ordinarily above the numbers, and that there is an assorting device and a retriever belt 139 for each row of magazines. It would be possible to use but one such magazine equipment at one end of the display belt so that characters carried by the display belt would be carried along one course and back by the other course of the display belt 116. Such an arrangement, however, would be undesirable because a given character would not become viewable upon the return side of the display belt until a considerable time after the display of the character on the first side of the belt had taken place. It is therefore preferable to have the set of magazines, assorting devices and retrieving belts duplicated at the two ends of the display belt. Under such circumstances the characters placed on the display belt 116 from the

magazines at one end will be detached from the display belt and stored in the magazines at the other end of the display belt instead of being carried around the whole course of the belt and returned to the magazines at the end of the belt from which the characters were first applied. It is of course understood that the magazines, etc., at the two ends of the belt are adapted for handling the same character plates.

The display belt 116 (see particularly Fig. 19) 10 is supported and driven by the pulleys 166 and 167. The pulley 167 has its axle mounted in adjustable and self-aligning bearings 168 and 169 and on such axle carries the gear 170 in mesh with the gear 171 driven by the electric motor 172. Also upon the axle of the pulley 167 15 is a grooved pulley 173 connected by a belt 174 with the pulley 175 fixed on the rotatable shaft 176, which also carries the pulleys 177 and 178 which respectively drive the retriever belts 179 20 and 180 at one end of the display belt. The display belt 116 drives the pulley 166 at its other end, which pulley is mounted upon an axle 182 journaled in the adjustable and self-aligning bearings 183 and 184. Also fixed upon the pulley axle 182 is the grooved pulley 185 which drives the shaft 186 through the belt 187 and pulley 188 fixed on the shaft 186. Also fixed upon the shaft 186 is the driving pulley 189 for the retriever belt 190 and also fixed upon the 25 shaft 186 is the before referred to pulley 191 driving the retriever belt 192. It will be observed that the axes of the pulleys 166 and 187 upon which the display belt runs are inclined slightly toward each other. This is for the reason that the steel display belt employed tends to creep downwardly upon the pulleys (their axes being vertical) and the inclination of the pulleys as referred to limits or balances out such downward creep. The slight inclination can be adjusted so as to accomplish the desired result as stated by adjusting the bearings 183 and 184.

The axle 182 of the pulley 186 also has fixed upon it the gear 191 which, through the gear 192 drives the gear 193 which is upon the shaft 194 (see Fig. 24) of the storage disk 52.

Also driven from the gear 192 is the gear 195 (see Fig. 31) fixed upon the shaft 196 which carries the cam 197 which forces together twice in each revolution the spring contacts 198 which are normally open. Also mounted upon the shaft 196 is the eccentric disk 199 journaled within one end of the connecting rod 200 (see Fig. 20), the other end of the connecting rod being pivoted at 201 in the link 202 for operating the character plate manipulating mechanism of the magazines as before referred to.

The electrical connections and energization of the apparatus may now be explained more in detail, reference being had particularly to Figs. 25 and 31. The incoming telegraphic code impulse sets into operation the distributor arm 18 which performs functions as already described. In this connection it may be observed that condensers of suitable capacity 203 are connected in parallel with the pin selector magnets 30 to 34 and 36 so that in high speed ticker service wherein the arm 18 would move very rapidly and the contact for a control magnet be maintained for a very short time, the condenser across the selector magnet will insure that sufficient energy is available to operate the magnet.

Also the first contact 17 is connected by the conductor 23 with the electro-magnets 204 and

205, so that circuit is made through them to ground at 206 and 207 respectively when the distributor arm 18 is on the first contact 17 which is in stop position.

The magnet 204 is for the purpose of controlling the driving motor 46 for driving the shaft 45 of the distributor arm. This motor 46, as described in connection with Fig. 24, drives the distributor arm through gearing 48 and 49 and a friction clutch 47. This friction clutch is a slip clutch which permits the motor to run when the distributor arm is held from movement by the dog 21, the clutch meanwhile slipping. The motor is started into and out of operation by means of control apparatus as will now be described. The usual plug 208 is inserted in the socket of a source of supply and circuit is completed from one terminal of the plug through the resistance 209 and the armature of the motor 46 through the contacts 210 to the other terminal of the plug. The resistance 209 is for speed regulating purposes and is controlled by a centrifugally controlled device 211 on the motor shaft for opening and closing a short circuit across the resistance 209 (see Figs. 39 and 40). If the speed increases beyond a certain limit the centrifugal effect of the speed of the motor will cause the contacts to open thereby throwing the resistance 209 into the motor circuit and reducing its speed, and on the other hand if the speed falls below a certain limit the contacts will be permitted to close thereby short circuiting the resistance 209 and speeding up the motor.

It will be apparent that the contacts will thus open and close so as to maintain the predetermined speed of the motor substantially constant. This centrifugal control of a motor is well known in the art, but an example of such a device is illustrated in Figs. 39 and 40, from which it will be seen that the device comprises a circular, pulley-like member having the hub 212, the face 213 and the web 214, the same being secured to the shaft 215 of the motor. Mounted upon but insulated from the hub 212 is the contact 216. Adapted to cooperate with the electrical contact 216 is the spring-mounted contact 217 which is biased to make contact when the motor is below a certain speed. This contact carries a centrifugal weight 218 which, when the speed of the shaft 215 exceeds a certain limit causes the contact 217 to be moved outwardly from contact 216 and break the circuit. The contact 216 is connected with a collector ring 219 upon the face 213 of the pulley, while the contact 217 is electrically connected with the collector ring 220 on the pulley face. External connections may be made with these collector rings by brushes 221 and 222 respectively bearing on the collector rings, which are respectively connected with the terminals of the resistance 209.

The contacts 210 which are spring mounted and biased to be normally closed are controlled to start the motor when a period of signalling is inaugurated and to stop the motor after the signalling period has terminated. In order to effect this operation a worm 223 is rotated through appropriate gearing by the motor 46 and a spring 224 tends to both urge an arm 225 away from the contacts 210 and also toward the worm. A pin 226 fixed in the end of the arm 225 engages in the thread of the worm 223 and there is a stationary stop 227 which limits the lateral movement of the arm 225 under the action of the spring 224. The arm 225 is pivoted at 228 to swing laterally

(longitudinally of the worm) and also pivoted at 229 to swing the pin 226 toward and away from the worm under the influence of the magnet 204 and the spring 224. When the magnet 204 is energized the pin 226 is moved out of the thread of the worm 223 and the arm 225 is moved about the pivot 223 against the stop 227 by the spring 224. When the magnet is deenergized the pin 226 is in engagement with the worm and travels along the same in a direction tending to open the contacts 210.

It will now be seen that when the initial starting impulse of a train of impulses corresponding to a signal is received, energization of the magnet 204 will swing the arm 225 about its pivot 223 thereby releasing the arm from the worm and the spring 224 will draw it into its initial position against the stop 227. The contacts 210 being thus closed the motor will start up and the worm be rotated. The pin 226 engaging the worm, the arm will travel along the worm tending to open the contacts 210 and stop the motor. The timing is so arranged, however, that during the ordinary succession of trains of impulses during a period of transmission, the arm 225 will not reach the contacts 210 before a new train has been started and the arm restored to its initial position. If, however, there is an unusually long time between the trains of impulses, such as would be the case where the operation of the apparatus had been discontinued for the time being, then the arm would travel far enough to open the contacts and stop the motor, thus avoiding the operation of the motor when the apparatus is not in use, this being done automatically instead of depending upon the fallible care of an operator to shut the motor down when its use is no longer required such as at the end of a day's run.

In order to drive the display belt and other apparatus in suitable timed relation thereto, apparatus is employed as will now be described.

The motor 172 is connected through a gear 171 with the belt drive as before referred to. The motor 172 (see particularly Fig. 31) derives its current from the usual socket plug 230 through a controlling resistance 231 in series with its armature, and the relay contacts 232. The resistance 231 is for the purpose of speed control of the motor being controlled by a centrifugally controlled short circuiting device, such centrifugal device being indicated at 233 and may be of the same structure as described in connection with the device 211 and the resistance 209.

The contacts 232 are for the purpose of starting and stopping the belt motor and are controlled by a relay magnet 234 which operates when energized to close the contacts against tension of a spring 235. The circuit of this magnet 234 is controlled by the normally closed spring contacts 236, the power being derived from any suitable electrical source as a battery 237. The reason for making use of the relay including the magnet 234 is that when the motor circuit is closed the current is comparatively large so that it is not desired to break such an amount of current upon the contacts 236. The contacts 236 are controlled by an arm 238 having a pin 239 adapted to engage within the thread of the worm 240 on the shaft 196. This arm 238, similar to the arm 225, is pivoted to swing toward and away from the worm at 241 and to swing along the worm by pivoting at 242. A spring 243 tends to force the arm into engagement with the worm 240 and also to draw it to its initial position against the stop 75 contacts 210.

244. The magnet 205 when energized tends to draw the pin 239 out of engagement with the worm, and when deenergized permits the spring 243 to move the arm in the opposite direction. 5 The shaft 196 upon which the worm is secured is driven through the display belt as before mentioned (see Fig. 1a). Also it will be apparent that the magnet 205 is energized at the first one of a train of incoming impulses, so that upon 10 the incoming of such first impulse the arm 238 will be withdrawn from the worm and retracted to its initial position against the stop 244 and the motor 172 has its circuit closed and is started up and, as the shaft 196 rotates, the arm 233 will 15 travel along the worm 240 in a direction tending to open the contacts 236. The timing is such that the arm 238 will not reach the contacts 236 to open them and stop the belt motor until after the last character set up of pins 53 in the storage 20 disk 52 has operated to apply the last character to the display belt and preferably will pass slightly beyond the last magazine as a further running of the belt would not be of damage, whereas it must surely continue running a sufficient length of time to permit the application thereto of all the characters corresponding to the impulse trains in a transmitted message received by and stored in the storage disk.

25 The magnet 205 is energized at each starting 30 impulse of a train of impulses so that the arm 238 is reset with each starting impulse, so that during the usual continuous operation of the apparatus for the receipt of messages, the travel of the arm 238 would not be sufficient to cause it to open the contacts 236, but if there should be a somewhat longer cessation of the receiving of messages, the arm 238 would travel sufficiently to open the contacts 236 and shut down the belt motor 172. The timing is such that ordinarily the time of disuse of the apparatus required for the shutting down of the motor 172 is substantially less than the time of disuse required to shut down the distributor motor 46. As a practical matter the timing would usually 45 be such as to cause the distributor motor 46 to shut down at the end of a comparatively long period after the termination of the usual business hours of a day, whereas the belt motor 172 would be shut down if there were any considerable period during the day when messages were not being received. It will be seen that the parts are so electrically and mechanically related that this desired timing can be brought about in a suitable predetermined manner.

50 55 The apparatus constructed and arranged as described operates as follows:

It will be observed that the distributor arm 18 moves at a high rate of speed of the order of 500 revolutions per minute, being driven from one motor as described. The display belt and its connected apparatus which includes the disk for operating the pins 53 and mechanism for the magazines for the character plates, are operated at a much lower speed from a separate motor. The incoming code signals start the rapid revolution of the distributor arm 18 so that the contacts of all the magnets 30 to 34 and 36 are traversed.

60 65 The speeds of the disk 52 and the distributor arm 18 may be adjusted so that the time of revolution of the distributor shaft 45 will be approximately the time between which one radial row of pins 53 leaves the transfer recess or point 60 and is succeeded by the next radial row of 75 pins, or the disk 52 may move slightly faster

than this. Also the magnets 30 to 34 and 36 having been rapidly successively energized as stated, the members 40 are thrust forward over those ones of the plungers 42 which have been selected, so that when the bail 43 descends it depresses the selected plungers which are then latched in depressed position so as to selectively depress the pins 53 of the next radial row of pins which reaches the transfer point after the setting of the plungers 42.

A radial row of pins having been thus set up as described it passes beneath the contact combinations *a* and *b*, etc., of which there is one corresponding to each of the magazines of the same character, for instance the *a* magazines. As soon as the plungers 42 have been depressed as indicated, the bail 76 withdraws the members 40 so that the apparatus is in readiness for a new set-up under a new code signal during the next revolution of the distributor arm 18.

The display belt and the disk 52 are connected together as explained so as to have a fixed ratio of movement.

It will be apparent that a point on the belt which is at the center of one magazine must move so as to be opposite the center of the next magazine between two successive character plate releases. The belt, therefore, must move the distance as indicated from one magazine to the next during each revolution of the distributor, that is to say between the receipt of two successive incoming code signals, and the time required for a set of pins to move from one contact combination to another, as from contact combination *a* to contact combination *b*, and this latter is also the same time that elapses between the passage of successive radial rows of pins 53 past the transfer point or recess 60. The result is that when a set-up of pins is made at the transfer point there will be reserved upon the display belt an area for the receipt of the character plate corresponding to that set-up and that area will be reserved until the magazine corresponding to that character is reached by the area (that is to say the area is in front of the magazine) when the proper character will be projected upon that area. No other character in the meantime can be projected upon this area of the belt. The result is that the characters will be attached to the belt in their proper order and in accordance with the receipt of the trains of impulses corresponding to the character selected. This does not necessarily mean that there can be no character plates projected on the belt until one for which the space has been reserved has been applied. On the contrary, in the meantime other characters may be projected upon the belt in their own proper areas.

It will be readily understood from the foregoing that each radial row of pins as it is selectively set-up at the transfer point 60 is carried in almost a complete revolution by the rotation of the disk, retaining the set-up until it reaches the depression 58 when all of the pins descend into this recess and are re-aligned or restored in readiness for any set-up at the transfer point 60.

Also it will be observed that the means for manipulating the character plates in a magazine, namely the claw plates 250 and the slides 262 and 263, are all interconnected with the display belt as to move in a definite time relation thereto and consequently with the other apparatus connected with the belt as before referred to.

The parts are so interconnected that for each movement of the display belt for a distance equal to that from the center line of one magazine to the center line of the next magazine the claw plates 250 and the slides 262 and 263 will make a complete cycle, that is a rearward and forward stroke, so that they will operate at a sufficient frequency to remove the plate from the retriever belt for each such distance of movement as stated, so that the extreme condition of two similar character plates in adjacent areas on the display belt is provided for.

The arms 278 are also adjusted to this timed operation of the arms 276 to assure that the arms 278 are set back of the forward plate in the magazine and ready to place the plate upon the belt under the force of the spring 273' when the plate shall have been released as described.

It will now be seen that the parts are connected in proper driving and timed relation so that there is always a supply of character plates in the magazines ready for ejection upon the display belt according to the selection of the code signals received and that the parts are properly operated so that different operations do not interfere with each other and there is no danger of piling up or jamming of the character plates at any time.

The contacts 96 which control the circuits for operating the magazines have their operating cam 197 so timed that the contacts 96 will take the arc of breaking the circuit because they will be opened while the contacts 71 and also the contacts 99 and 100' or 105' of any operative contact combination remain closed. Also the closing of the contacts 96 is so timed by the cam 197 with relation to the operation of the belt 277 that the strip 273 is at its rearmost position so that the arms 278 are free to operate under the spring 273' to eject the foremost plate upon the display belt.

It will be observed that the exhibition or display may be made of any desired length by making the display belt of appropriate length. A greater length of belt increases the time of display of any given notation and also the notations viewable at any time may be greater in number or length.

Referring to Figs. 33, 35, 36, 37, 38, 42 and 43, there is shown a modification wherein the characters are selected by means of a printed tape, such as the usual "ticker" tape. Such a device is especially useful where the usual printing stock quotation "ticker" is telegraphically controlled and it is desired to obtain several displays of the quotations but without going to the expense of telegraphic charges for each display. To this end the apparatus is controlled by the usual printed "ticker" tape so that the display device exhibits characters in accordance with those upon the tape, the tape being preferably fed directly into the apparatus from the "ticker" which prints the tape.

The five selector magnets 310, 311, 312, 313 and 314 and the "shift" magnet 315 correspond with the selector and "shift" magnets 30 to 34 and 36 of the structure shown in Figs. 24, 25 and 31 and such selector and "shift" magnets, as in the apparatus of Figs. 33 and 31, operate to set up different combinations of pins which operate in the same manner as in the preceding apparatus to select the character plates for ejection upon the display belt, apparatus of the present modification being the same as that of the preceding apparatus except for the manner of controlling the

selector and shift magnets. The magnets 310 to 314 inclusive are all connected with a conductor 352 which establishes a connection with the contacts 350 and 351. The other terminals of the magnets are respectively connected with the conducting rings 318 to 322 inclusive mounted upon the back of the fixed disk 323 of insulation. From these rings 318 to 322 inclusive are metal contacts projecting through the insulation to the front side opposite the rings where they may be engaged by the brushes 324 to 330 upon the brush arm 331 as it rotates with the shaft 332. It will be seen that there is one brush on the arm corresponding with each of the rings 318 to 322 inclusive and also brush 332' in continual contact with a ring 333'. The contacts extending through the plate of insulation for engagement with the brushes, as will be seen, are arranged in concentric circles corresponding to the rings 318 to 322 inclusive, and are also arranged in radial lines as for instance is illustrated by the radial row of contacts 335 to 338 inclusive. The contacts are also arranged in two groups separated by the blank areas (having no contacts in them) 339 and 340, the blank sector 340 being of considerably greater width than the sector 339. There are as many radial rows of contacts on the front of the plate in each of the right and left hand groups as there are desired character combinations and there is a resistance controlling contact 334 for each radial row. Only rows at the beginning and ending of each of the groups being shown, intermediate rows being omitted to avoid complication in the drawings.

The outer row 334 of contacts of the group to the right (see Fig. 35) of the blank sectors 339 and 340 have taps connecting them with the resistance 341, while the outer circle of contacts 334 of the group to the left (see Fig. 35) of the sectors 339 and 340 are tapped at intervals into the resistance 342. The resistance 342 and also resistance 341 are each continuous from end to end but, to simplify the drawings the intermediate portion of each has been omitted.

The contacts in one of the groups separated by the blank sectors is for furnishing the selection of one kind of characters, say letters, while the other group on the other side of the blank sectors is for the purpose of selecting another class of characters as numerals. It will be seen that in the different radial rows of contacts different ones of the rings on the back of the disk are connected with contacts appearing upon the other side so that the different radial rows of contacts serve to connect different combinations of selector magnets as the brushes and arm sweep over them. The brush arm is connected through conductor 343 with the ground at 317 through the battery 344 and controlling apparatus as will be herein-after referred to.

It will be noted that as the brushes with the brush arm move over the left hand group of contacts terminating at the blank sectors, not only will contacts be made with the successive radial lines of contacts to connect selected ones of the magnets 310 to 315 through the battery with ground as described, but the outer end brush on the arm will also successively connect the taps from the resistance 342 through the brush arm with the conductor 343. This resistance is connected through the conductor 345 with the terminals of the "bucking" coils 346 in parallel to ground at 347. Similarly the brush arm in moving over the outer circle of the right hand (Fig. 35) group of contacts will successively connect

the taps from the resistance 341 with the conductor 343.

In the right hand (Fig. 35) group of contacts is also the semicircular conductor ring 322' engaging the next to the innermost brush 324, such ring being connected with one terminal of the "shift" magnet 315.

The brush arm moving in the direction of the arrow *a* (Fig. 35), the resistance 342 will be all inserted in the circuit of the "bucking" coils when the brush arm leaves the blank sector 340 and enters upon the left hand contact group, and will progressively remove resistance from the circuit as it proceeds over that contact group. As the brush arm leaves the blank sector 339 and enters upon the right hand contact group all the resistance 341 will be inserted in the circuit of the bucking coils and will be progressively cut out as the arm moves over that group.

These "bucking" coils are adapted to oppose the magnetism of the light controlled coils 348 of the polarized relay connected in parallel and controlled by the light control as will be hereinafter described. These "bucking" and control coils 346 and 348 are the operative coils in relation to the polarized relay having the armature 350 which, when the light controlled magnetism predominates, is biased thereby away from the contact 351 whereby circuit is open between the conductor 352 connected with the relay armature and the conductor 353 connected with the contact 351, but when the magnetism of the "bucking" coils predominates over the magnetism of the coils 348, the polarity of armature 350 will be reversed and contacts 350 and 351 will close.

The current flowing in the coils 348 is controlled by two photo-electric cells 554 and 555 included in separate compartments 356 and 357 having the openings or windows 358 and 359, admitting the controlling light to the compartments and to the cells respectively, reflectors 358' and 359' respectively directing the light to the cells. Above the windows 358 and 359 is passed in close proximity thereto the usual printed tape 360 having, as is usual, the letter line 361 and numeral line 362, the printed characters being relatively opaque and the tape relatively transparent. Each one of these characters (letters and numerals) usually has a characteristic area of its own, different from others or by altering the design of the type, if necessary, may be made to have a different area from the others. Consequently these characters in passing the windows will operate as light shutters to different degrees, for instance the letters A and B will occupy different areas on the tape and therefore will present different areas of shutters and therefore cut off the light to a greater or less degree from the compartment, and the photo-electric cell corresponding to the letter row. Similarly the numerals will, as for instance 2 and 3, be of different area and operate, in passing the window corresponding to the numeral line, cut off the light to different degrees from the photo-electric cell corresponding to that window. The photo-electric cells each have one terminal connected with the conductor 363 which passes through the current amplifier 364 of any suitable construction and therefore not shown in detail, and thence through the battery 365 with the contact 366 adapted to be alternately moved into and out of engagement with the contacts 367 and 368, the contact 366 being spring biased into engagement with the contact 368 but movable therefrom

by the cam 369 into engagement with the contact 367. The contacts 367 and 368 are respectively connected with the other terminals of the photo-electric cells. The one photo-electric cell, corresponding for instance to numerals, will therefore be connected through the amplifier 364 with the relay coils 348, according to whether the contact 366 is in contact with the contact 367 or contact 368.

The shaft 332 is driven through suitable gearing 370 by a suitable motor 371 which runs continuously (driving the brush arm 331 continuously) as long as the apparatus is in use. Also fixed upon the shaft 332 is the cam 372 having the projection 373 adapted to force closed the normally open contacts 374 one of which is connected to ground at 375 and the other connected through the conductor 376, the magnet 377, and the battery 378 to ground at 379, the magnet 377 controlling the ground connections for the selector magnets, insuring that such connection shall be cut off after the brush arm has arrived at the space 340 and prior to the feeding of the tape by cam 380, thereby insuring that the contacts 397 shall be opened and the character not repeated in case the "ticker" has stopped, thus permitting the brush arm to rotate normally, and when the brush again enters upon the selector contacts, the contacts 397 will be closed upon resumption of operation of the "ticker."

Also fixed upon the shaft 332 is a disk 380 having a recess 381 into which may drop the roller 382 rotatably mounted in the end of the crank arm 383 fixed upon a rocking shaft 384 upon which is fixed the arm 385, the spring 386 causing the roller 382 to drop into the recess 381 when they are in register and permitting the arm to ride up out of the recess 381 upon the circular periphery of the disk 380. When the roller 382 enters the cam recess 381 the shaft 384 will oscillate and move the arm 385 in an upward direction so that its end comes against and pushes aside the inclined end surface of the spring-pressed retaining dog 387 thereby permitting the arm 388 pivoted upon the shaft 389, to move downwardly under the influence of the spring 390. When the arm 388 thus moves downwardly the pawl 391 pivoted upon the arm 388 will engage the ratchet wheel 392 fixed upon the shaft 389 and turn the same one step thereby turning the drum 393, also fixed upon the shaft 389, which therefore advances the printed tape 360 by reason of its frictional gripping between the drum 393 and the spring-pressed idler roll 394.

It will be observed that the arm 385 is raised to set the arm 388 in its full elevated position whenever the brush arm 331 is over the dead area 340. It is thereby insured that the beginning of a step forward of the tape will always take place only at the beginning of a revolution of the arm 331 so that the movements of the tape will always be in step with the revolutions of the distributor arm no matter whether the "ticker" stops, and so interrupts the movement of the tape, or not, it being observed that upon stopping of the "ticker" the tape will also stop because the spring 390 is not of sufficient strength to pull the tape out of the "ticker" and the arm 388 remains in the upper position locked by retaining dog 387 after arm 385 descends. This prevents missing a character, if the "ticker" stops and starts out of phase with the brush arm.

Also engaging with the teeth of the ratchet wheel 392 is a pin on an arm 395 pivoted to a

stationary part of the apparatus. A spring 396, secured at one end to the pawl 391 and at the other end to the arm 395, tends to hold them in engagement with the ratchet wheel 392.

When the pawl 391 moves the ratchet wheel forward a step as described, the detent on the pivoted arm 395 will ride over a ratchet tooth and push outwardly against the spring-pressed pivoted arm 396' (fibre tipped where it bears against the arm 395) forcing the upper end of arm 396' outwardly against its spring tension, and closing the contacts 397. The spring latch 398 controlled by the magnet 377 will then spring into position to hold the arm 396' to maintain the contacts 397 closed and thus close the connection from the contact 351 of the polarized relay through conductor 353 to ground at 399.

After one set of selector magnets has been energized, the current is cut off so that all following segments will not be energized. This is accomplished by the relay 500 which is in multiple with the selector magnets and is shunted by the condenser 501 to insure operation where the opening and closing of the supply circuit is exceedingly rapid. This relay controls two separate circuits. The upper pair of normally-closed contacts 502, and of which the movable one is mounted upon but insulated from the contact 503 mounted on the armature 504 of the relay 500, disconnect the battery after the condensers are charged and before the distributor brush has made contact with the next radial row of segments. The armature 504 and its contact 503 then continue down to engage the contact 505 to close the circuit of the wipe out magnet 377 from ground at 506 through contacts 503 and 505, conductor 376, magnet 377 and battery 378 to ground at 379.

Referring to Fig. 37, the imprinted tape 507 is fed from the tape roll 508 in the conventional "ticker" to the printing wheel 509 by which the tape is printed and then passes on through the feeding mechanism 510. Thence the printed tape 507 passes over the windows 358 and 359 in the casing 511 for the photo-electric cells, the tape being resiliently pulled taut by a mechanism generally indicated at 512 and more particularly described hereinbefore. A strong light may be projected from a suitable source 513 and concentrated on the windows to affect the photo-electric cells under the control of the characters on the tape.

In the operation of the apparatus of Figs. 35 to 38, 42 and 43, the printed tape is advanced over the light receiving apertures or windows, one character at a time at a speed slightly faster than the source of supply which may conveniently be the conventional high speed "ticker" used in brokerage houses. Inasmuch as the printed tape has to be advanced over the receiving apertures referred to, the tape will be kept taut and free from slack at all times.

The shaft 332 operates the distributor brush arm 331. The speed of the brush arm is such that it makes one revolution for each character coming in front of the photo-electric device. The disk 380 is so placed upon the shaft 332 that it will operate the feed mechanisms through the shaft 384 so that the tape will be moved forward one character space for each revolution of the shaft 332 and therefore of the distributor arm. This feeding forward of the tape will take place while the brush arm is over the dead space 340. Also the cam 369 is so placed that the contact 366 is in engagement with the contact 367.

by reason of the fact that the contact 366 is in insulated engagement with the cam portion of small radius. This closes the circuit for the photo-electric cell 355 which is that corresponding to numerals on the tape.

The distributor arm then turning in the direction as indicated will sweep over the various rows of radial contacts and also the circumferential row of contacts 334 until it comes to the dead space 339. In passing over the contacts of the circumferential row 334 resistance 342 will be gradually cut out causing a gradual increase in the current in the "bucking" coils 346 on the polarized relay. In the coils 348 of the polarized relay is a current which depends upon the amount of light reaching the photo-electric cell 355 through the window 359, this depending upon the area of the window which is closed by reason of the area occupied on the tape by the particular numeral in front of the window and the area of each numeral is different from that of every other numeral so that each will have its own distinguishing effect upon the photo-electric cell.

The current in the "bucking" coils 346 starting from a low minimum value, lower than any current in the coils 348 due to the photo-electric cell, will gradually be built up until the magnetic effect of the coils 346 slightly exceeds that of the coils 348. The magnetic effect of the "bucking" coils having thus become slightly predominating over that of the coils 348, the armature will be subjected to an opposite polarity and will consequently move to its other extreme, closing the contacts 350 and 351. This closes one side of each of the magnets 310 to 315 inclusive to ground. The distributor brush arm 331 being connected with the battery it will be apparent that those ones of the selector magnets 310 to 314 inclusive will be energized, which have terminals connected with contacts in the radial row upon which the brushes of the distributor arm rests when the contacts 350 and 351 are closed as described. It will further be apparent that the radial row of distributor contacts upon which the distributor arm brushes rest at such time depends upon the current from the photo-electric cell which is controlled by the character over the window of that cell so that such character will control the selection of the magnets 310 to 314 inclusive. If there is no character in front of the window of the photo-electric cell, the light will be so much in amount that the current from the photo-electric cell, in the coils 348 will never be equaled by that in the "bucking" coils 346, so that no operation of the selector magnets will take place and contacts 350 and 351 remain open.

The brush arm having reached the dead spot 339 it will then enter upon the group of contacts to the right (see Fig. 35) of the dead spots 339 and 340.

Prior to the entry of the brush arm on to this group of contacts, namely while it is over the dead spot 339, the cam 369 will have been turned to such position that the contact 366 is raised to the periphery of the cam of larger radius and therefore the contact 366 is moved into engagement with the contact 367 thereby connecting the photo-electric cell 354 (affected by the letter characters) in operative relation to the polarized relay comprising the coils 346 and 348. Again beginning with its entry upon the group of contacts referred to, the brush arm will gradually cut out the resistance 341 until such time as the effect of the current through the "bucking"

coils 346 slightly exceeds the magnetic effect of the current in the light coils 348 when the contacts 350 and 351 will be closed with effects as previously described.

- 5 The current in the coils 348 being dependent upon the current from the photo-electric cell 354 and consequently upon the characteristic area of the letter in front of the window, the contacts 350 and 351 will be closed when the brush arm 331 occupies a position in its rotation where its brushes are upon a radial row of contacts of such of the selector magnets 310 to 315 as correspond to the letter before the aperture of the photo-electric cell.
- 10 15 Immediately after the circuits of the magnets 310 to 314 or 315 have been closed the battery should be cut off in order to prevent energization of any of the magnets through the next succeeding radial row of contacts on the distributor.
- 20 This is accomplished by means of the relay 590 which is connected in parallel with the selector and shift magnets which attracts its armature and breaks the battery connection at the contacts 502 as before referred to. The armature of the relay continuing downward closes circuit for the magnet 377 which removes the latch 398 from the lever 396', permitting the last to move inwardly and open the contacts 397, thus permanently opening the circuit until the lever 396' is reset by the feeding of another character into position before the window.

The feeding device for the tape whereby a new character is moved in front of the window is operated while the distributor brush arm 331 is over the blank area 346. This is accomplished by locating the recess 381 on the disk 380 in such position that the arm 332 will rock the shaft 384 to accomplish the feed while the distributor brush is over the blank space 346. This operation re-establishes circuit for the selector magnets (subject to control of the distributor contacts) at the contacts 397.

letter B which covers the largest area on the tape and therefore excludes the greatest amount of light from the photo-electric cell and consequently the magnetism in the polarized relay, due to the photo-electric cell, is least. M is the letter next lower in area and consequently the magnetism in the polarized relay due to the light controlled coils will be represented in the space between the first horizontal line above the zero line and the second horizontal line and is progressively decreased in light shut-off area up to the character of least shut-off area, namely a period at the top, and the magnetism in the polarized relay due to the light controlled coils will be increased accordingly. The horizontal distances on the base line represent a different angular position of the distributor, that is the different resistance connected segments. Inasmuch as the resistance in the "bucking" coil circuit is controlled by the positioning of the segment connected with the resistance upon which the brush arm rests, the abscissae of this curve are also proportional to the resistance in the "bucking" coil circuit and the current and the magnetism is inversely proportional thereto. The result is a curve as shown by the heavy black line in the figure from which it will be seen that just prior to the entry of the brush arm upon the resistance segment number 1, the circuit through the "bucking" coils will be open or on the dead spot 340 and the magnetism thereof will be zero. When the brush arm enters upon the number 1 resistance segment the magnetism in the "bucking" coil will be represented by the first vertical section of the curve. This value of the magnetism of the "bucking" coil will remain as shown by the first horizontal section of the curve until the number 2 resistance segment is reached when, a section of the resistance having been cut out, the current and magnetism in the "bucking" coil will rise according to the second vertical section of the curve, and so on as the various resistance segments are cut out the magnetism due to the "bucking" coils will be increased by increasing increments as shown by the curve. When the magnetism in the "bucking" coils slightly overcomes the magnetism due to the light controlled coils of the polarized relay the armature is attracted in one direction, i. e., its contacts closed. Thus current according to the graph of Fig. 33, and the magnetism due to the light controlled coils, when the character M is before the window, is represented by the same value that is between the second and third horizontal lines above the zero line, and therefore when the third resistance segment is contacted by the distributor brush arm the magnetism of the "bucking" coils will rise to a value slightly greater than that due to the light controlled coils and the relay armature will accordingly be moved as described. Under such circumstances the radial row of contacts corresponding to the set-up of the selector magnets for the character W will be contacted by the brush arm and the set-up of the magnets accordingly made. This operation of overcoming the magnetism of the light controlled coils in the polarized relay by the "bucking" coils, will occur at different values of the magnetism of the "bucking" coils corresponding to the various characters such as letters or numerals. The different values at which this overcoming of the light controlled coils by the "bucking" coils will occur for the

different characters will appear from the graph of Fig. 38.

It will also be observed that the cutting out of the resistance whereby the "bucking" coils are controlled is accomplished by a rotary movement of the distributor brush arm and that the overcoming of the magnetism of the light controlled coils in the relay will take place when the distributor brush arm is in engagement with a row of radial contacts of the distributor which corresponds to the character before the aperture of the photo-electric cell, so that the operation of the polarized relay is a function of the angular position of the distributor brush arm and the operation of the polarized relay will always take place when the distributor brush arm is in a certain angular position and makes contact with a certain radial row of contacts which represents the set-up of the selector magnets corresponding to the character before the aperture of the photo-electric cell.

Figs. 42 and 43 are enlarged views of the apertures or windows, which are of predetermined area, of the photo-electric cells graphically illustrating the difference in areas covered by the different characters on the tape, showing the letter B which probably occupies the largest area and the period which occupies the smallest area of any of the probable characters used and the blank space that permits a maximum of light to pass.

It will be observed that all of the selector magnets 310 to 314, and also the shift magnet 315 when it is called into operation are simultaneously energized and deenergized. Magnets 310 to 315, with their controlling mechanism (see Fig. 35) can be substituted for the magnets 30 to 34 and 36 and their controlling mechanism in the apparatus of Fig. 31. Under such circumstances, however, the plungers 42a corresponding to the plungers 42 of the structure of Figs. 24, 25 and 31 would each be operated (see Fig. 33) by a pivoted armature 518 normally held elevated over the plunger by a spring 515 but movable downwardly by the energization of a magnet 516, the magnet 516 being typical of the magnets 316 to 315, each of such magnets having an armature and operating the plunger 42a in the manner as described.

Referring to Fig. 34 there is therein shown apparatus for operating the selective display mechanism of a code operated system, from the usual "ticker," the usual tape from the "ticker" preserving a record of the messages received. The device constitutes in effect a means for retranslating the code signals from the rotated type wheel as appearing on the usual "ticker" into the original code, inasmuch as provision is made for energizing magnets according to the code received message, as if those magnets had been energized directly by the telegraphic code impulses and such magnets may then be used to actuate any apparatus in accordance with the code as by perforating a controlling tape, controlling a display device as hereinbefore referred to, and for other operations which it is desired to control in accordance with the original telegraphic code.

The code signals are received in the usual manner (usually in Baudot code but not limited thereto) over the telegraphic line 400 and operate upon the usual "ticker" mechanism 401 including the printing wheel 402 in the usual manner. The printing wheel has as is usual the circumferential row of letter type 403 and the circumferential row of numeral type 404. These are printed upon the paper tape 405 (supplied from a roll not shown) by bringing the charac-

ter to be printed, if a numeral, opposite the hammer 406 for forcing the paper against the type, or if a letter, the letter to be printed is brought opposite the hammer 407 for the same purpose as the hammer 406, the hammers thus cause printing of the letter or numeral respectively upon the tape and the proper hammer is caused to operate in the well known "ticker" by means of the usual "shift" impulse of the code. The hammers 406 and 407 are pivoted at 408 and their movement away from the type wheel is limited by a stationary stop 409. The apparatus as thus far described is well known in the ordinary "ticker".

Fixed upon an extended portion of the shaft 410 of the "ticker" and rotating therewith is a brush arm 411 having the brushes 412 to 416 inclusive. Concentric with the shaft 410 is a stationary disk 417 of insulation having upon its rear face the circular conducting rings 418 to 422 inclusive, these rings being connected by the conductors 423 to 427 inclusive with the five code selector magnets 428 to 432 inclusive. The "shift" magnet 433 is connected by the conductor 434 with the contact 435 as will be hereinafter referred to.

At various points around its circumference each of the rings has contacts connected to it and projecting through the disk 417 so that they may be engaged by the brushes on the arm 411. These contacts, it will be seen, are arranged in circumferential rows over the rings 418 to 422, and are also arranged in radial lines containing a number of contacts depending on what rings have contacts brought through the disk for that particular radial line, thus on the radial line 436 are the four contacts 437 brought through respectively from the rings 419 to 422 inclusive, this representing the combination of a particular code character, and similarly on the radial line 438 are arranged the three contacts 439 connected with the rings 418, 419 and 422 respectively representing another combination according to another code signal. These radial rows of contacts may be made of any desired number and combination to represent the number of character signals to be provided for and each radial row has contacts corresponding to the magnets to be energized in accordance with the code signal received. As the brush arm 411 is rotated with the shaft 410 it brushes over and contacts with the faces of the contacts extending through the insulating disk from the rings at the rear, the brushes 412 to 416 inclusive respectively engaging the contacts of the circumferential rows corresponding to the rings 418 to 422 inclusive. The brush arm 411 also carries the contact brush 440 which is in constant engagement with the conductor ring 441 on the front face of the insulating plate 417. The brush arm 411 is of conducting material so that there is always electrical connection between the brushes 412 to 416 inclusive and also with contact brush 440. The radial rows of contacts on the front of the insulator disk, as referred to, are so located angularly about the shaft that when a character on the "ticker" wheel is in printing position, i. e., opposite the hammers 406 or 407, the brush arm 411 will be in such position that the brush contacts will be in contact with the radial row of contacts corresponding to the code set up of such character.

When both the hammers 406 and 407 are in their retracted position against the stop 409 the circuit of the battery 442 from the ground at

443 will be open at the contacts 444 and 445. If, however, a character in the letter row has been moved into printing position and the hammer 407 moved against it, such turning of the hammer will move the contact 446, fixedly connected to the hammer 407, against the contact 445. Circuit will then be completed, from the ground at 443, through the battery 442, contacts 445 and 446, and the conductors 443 and 451, with the ring 441 and thence to the brush 440. Circuit will thence be made through those of the brushes 412 to 416 inclusive which are connected with contacts in the radial row of contacts beneath such brushes at the time and circuit will thus be made to the corresponding ones of the selector magnets 428 to 432, inclusive, and thence to ground at 449. As before stated, the radial row of contacts in the disk 417 through which connections are thus made will correspond with the code set up of the character of the printing wheel on the "ticker" which is in printing position and accordingly those of the selector magnets 428 to 432 are energized corresponding to that code set up. If, however, the code signal received by the "ticker" should correspond to a numeral, and therefore the hammer 406 should be thrown against the tape, such movement of the hammer will move the contact 447 which is fixed upon the hammer, into engagement with the contact 444. This closes a circuit through the conductors 450 and 448 to the conductor ring 441 where circuit is made through the magnets 428 to 432, inclusive, in accordance with the code set up of the character being printed. Also circuit will be made from the conductor 450 through the conductor 451 and contacts 446 and 435 and the conductor 434 through the "shift" magnet 433 to the ground at 449. It will be observed that when a character in the letter row is to be printed and the hammer 407 is actuated to print, the contact 446 is removed from contact with the contact 435 so that the circuit through the "shift" magnet 433 is broken.

It will now be seen that with the apparatus as described not only will there be the record of the usual printed tape but that the appropriate selector magnets corresponding to the set-up of the particular character being printed will be energized and the "shift" magnet will be energized or not according to whether a numeral character or letter character is being printed. This selective energization of the selector magnets and the "shift" magnet may then be used to operate a display device as hereinbefore described or for any other use where it is desired to operate apparatus in accordance with the code.

The apparatus of Fig. 34 may be employed for controlling the display mechanism as set forth in Figs. 1 to 32 and 39 to 41, inclusive, by substituting the magnets 428 to 433, inclusive, for the magnets 30 to 34, inclusive, and 36 in the controlling mechanism of Figs. 24 and 31, each of the magnets 428 to 433 when so substituted being provided with the plunger operating mechanism as shown in Fig. 33 as before referred to.

The magnet 475, connected between the ring 441 and ground at 476, controls the belt motor and corresponds to the magnet 285 of Fig. 31, it being apparent that the magnet 475 will be energized whenever either of the hammers 406 or 407 is operated to print.

While the invention has been illustrated in what is believed to be its best application, its apparatus may have other embodiments and its

method may have its details varied, without departing from its spirit. The invention of apparatus is not therefore limited to the structures shown in the drawings nor the method to the precise details recited.

What I claim is:

1. In a display device the combination with a movable surface, of characters adapted to be applied thereto, means for selectively applying said characters to said surface, means for removing the characters from the said surface, magazines for the said characters respectively and means for selectively placing the removed characters in the magazines.

2. In a display device, the combination with a movable display carrier, of a plurality of classes of character members separate from and adapted to be attached to said carrier means for selecting said character members of the different classes, and means for bodily attaching the selected character members of the different classes to said carrier, the said carrier having different areas to which the different classes of character members are respectively applied, which areas are displaced transversely of the movement of the carrier.

3. In a display device the combination with a movable display carrier, of character members separate from and adapted to be attached thereto, magazines for said members and means for selectively applying said characters from said magazines to said carrier, said magazines being located at positions along said carrier at which the character members are applied.

4. In a display device the combination with a movable display carrier, of character members separate from and adapted to be attached thereto, magazines for said members and electro-magnetically controlled means for selectively applying said characters from said magazines to said carrier, said magazines being located at positions along said carrier at which the character members are applied.

5. In a display device the combination with a movable display carrier, of character members separate from and adapted to be attached thereto, magazines for said members, means for selectively applying said characters from said magazines to said carrier, means for removing the said members from the said carrier and means for selectively placing the removed character members in the said magazines.

6. In a display device the combination with a movable display carrier, of character members separate from and adapted to be attached thereto, magazines for said members, electro-magnetically controlled means for selectively applying said characters from said magazines to said carrier, means for removing the said members from the said carrier and means for selectively placing the removed character members in the said magazines.

7. In a display device the combination with a movable display carrier, of character members separate from and adapted to be attached thereto, magazines for said members and means for selectively applying said characters from said magazines to said carrier, said magazines being arranged transversely of said carrier.

8. In a display device the combination with a movable display carrier, of character members separate from and adapted to be attached thereto, magazines for said members and means for selectively applying said character members from said magazines to said carrier, said magazines

being arranged in a row extending longitudinally of the travel of said carrier.

9. In a display device the combination with a movable display carrier, of character members separate from and adapted to be attached thereto, magazines for said members and means for selectively applying said characters from said magazines to said carrier, said magazines being arranged in rows, each row extending longitudinally of the travel of said carrier and said rows being arranged transversely of said carrier.

10. In a display device the combination with spaced supports, of an endless display carrier having display area between said supports and loops about said supports, of character members separate from and adapted to be attached thereto, and separate groups of magazines for said members adjacent both loops respectively of said carrier and means for selectively applying said characters from said magazines to said endless carrier.

11. In a display device the combination with spaced supports, of an endless display carrier having display area between said supports and loops about said supports, of character members separate from and adapted to be attached thereto, and separate groups of magazines for said members adjacent both loops respectively of said carrier, means for selectively applying said characters from said magazines to said endless carrier and means for removing said members from said carrier and selectively placing them in said magazines.

12. In a display device the combination with spaced supports, of an endless display carrier having display area between said supports and loops about said supports, of character members separate from and adapted to be attached thereto, and separate groups of magazines for said members adjacent both loops respectively of said carrier, means for selectively applying said characters from said magazines to said endless carrier, and means for removing said members from said carrier and selectively placing them in said magazines, the character members applied to the said carrier at one end being placed after removal therefrom in the magazines at the other end of said carrier.

13. In a display device the combination with spaced supports of an endless display carrier having display area between said supports and loops about said supports of character members separate from and adapted to be attached thereto, and separate groups of magazines for said members adjacent both loops respectively of said carrier, means for selectively applying like character members simultaneously at both ends of the belt.

14. In a display device the combination with a movable display carrier, of character members separate from and adapted to be attached thereto, means for selectively bodily attaching said members to said carrier, a code controlled means for controlling said selective attaching means, a motor for driving said code controlled means and timed means for controlling said motor.

15. In a display device the combination with a movable display carrier, of character members separate from and adapted to be attached thereto, means for selectively bodily attaching said members to said carrier, code controlled means for controlling said selective attaching means, a motor for driving said code controlled means, a motor for driving said carrier, timed

means for controlling said carrier motor and timed means for controlling said motor for driving said code controlled means.

16. In a display device the combination with character members, of a movable carrier to which said character members are adapted to be attached, a plurality of magazines for said character members distributed longitudinally of the movement of said carrier, means controlling the attachment of said members to said carrier, a plurality of sets of code controlled members, each set being adapted to be set up in different combinations in accordance with the code signals, means for controlling the set up of said code controlled means according to predetermined code signals, means for moving said sets of code controlled members past said controlling means, each set of said code controlled members being controlled by said controlling means as it passes the same to relatively set up the said code controlled members in a combination corresponding to a code signal, a plurality of sets of members controlling the said character members, the last sets of members being distributed longitudinally of the movement of said code controlled members, and each set being adapted to be operated only by its own particular set up of the said code controlled members corresponding to the code signal received and the character member which it controls.

17. In a display device the combination with a plurality of character members, of a movable display carrier to which said characters are adapted to be applied, a plurality of selector magnets, means for selectively energizing said selector magnets in accordance with electrical impulses received in accordance with a predetermined code, a rotating disk, a plurality of radial rows of pins in said disk, means for setting up the pins of different rows in different relative combinations corresponding to the energization of said selector magnets, a plurality of sets of character applying controlling members distributed about said disk, each of the last mentioned sets corresponding to a character and adapted to be operatively affected to control the character by its own particular set up in a row of said pins corresponding to the code signal received and the corresponding character, means for maintaining the set ups of the rows of pins as they pass said sets of character applying controlling members and means for releasing each row of pins from a set up as determined by said selector magnets, in readiness to be again selectively acted upon by said selector magnets.

18. In a display device the combination with a plurality of character members, of a movable display carrier to which said characters are adapted to be applied, a plurality of selector magnets, means for selectively energizing said selector magnets in accordance with electrical impulses received in accordance with a predetermined code, a rotating disk, a plurality of radial rows of pins in said disk, means for setting up the pins of different rows in different relative combinations corresponding to the energization of said selector magnets, a plurality of sets of character applying controlling members distributed about said disk, each of the last mentioned sets corresponding to a character and adapted to be operatively affected to control the character by its own particular set up in a row of said pins corresponding to the code signal received and the corresponding character, means

for maintaining the set ups of the rows of pins as they pass said sets of character applying controlling members and means for releasing each row of pins from a set up as determined by said selector magnets, in readiness to be again selectively acted upon by said selector magnets and a common means for driving said carrier and said disk.

19. In a display device the combination with 10 a plurality of character members, of a movable display carrier to which said characters are adapted to be applied, a plurality of selector magnets, means for selectively energizing said selector magnets in accordance with electrical impulses received in accordance with a predetermined code, a rotating disk, a plurality of radial rows of pins in said disk, means for setting up the pins of different rows in different relative combinations corresponding to the energization 15 of said selector magnets, a plurality of sets of character applying controlling members distributed about said disk, each of the last mentioned sets corresponding to a character and adapted to be operatively affected to control the character by its own particular set up in a row of said pins corresponding to the code signal received and the corresponding character, means for maintaining the set ups of the rows of pins as they pass said sets of character applying controlling members and means for releasing each row of pins from a set up as determined by said selector magnets, in readiness to be again selectively acted upon by said selector magnets and a common means for driving said carrier and said disk, magazines 20 for said character members, electro-magnets respectively controlling the application of character members from said magazines to said carrier, and contacts controlling the last mentioned electro-magnets, said contacts being respectively controlled by the said sets of character applying controlling members.

20. The combination with a plurality of character members, of a movable carrier to which said character members are adapted to be attached, 45 a plurality of magazines for said character members distributed longitudinally of the movement of said carrier, means controlling the attachment of said character members to said carrier, a plurality of code controlled members, each set being 50 adapted to be set up in different combinations, means for controlling the set up of said controlled members according to predetermined code signals as said sets of code controlled members are moved past said set up controlling means, 55 means for moving said code controlled members, a plurality of sets of members controlling said character attachment controlling means, the last mentioned sets of members being distributed along the path of movement of said code controlled members and adapted to be selectively operated according to the respective set ups of said code controlled members as they are moved past them.

21. The combination with a plurality of character members, of a movable carrier to which said character members are adapted to be attached, a plurality of magazines for said character members distributed longitudinally of the movement of said carrier, means controlling the attachment 70 of said character members to said carrier, a plurality of sets of code controlled members, each set being adapted to be set up in different combinations, means for controlling the set up of said controlled members according to predetermined code signals as said sets of code controlled

members are moved past said set up controlling means, means for moving said code controlled members, a plurality of sets of members controlling said character attachment controlling means, the last mentioned sets of members being distributed along the path of movement of said code controlled members and adapted to be selectively operated according to the respective set ups of said code controlled members as they are moved past them, said moving means and said carrier being connected together in timed relation.

22. In a display device the combination with a plurality of character members, of a movable display carrier to which said characters are adapted to be applied, a plurality of selector magnets, means for selectively energizing said selector magnets in accordance with electrical impulses received in accordance with a predetermined code, a rotating message storage disk, a plurality of radial rows of pins in said disk, means for setting up the pins of different rows in different relative combinations corresponding to the energization of said selector magnets, a plurality of sets of character applying controlling members distributed about said disk, each of the last mentioned

sets corresponding to a character and adapted to be operatively affected to control the character by its own particular set up in a row of said pins corresponding to the code signal received and the corresponding character, means for maintaining the set ups of the rows of pins as they pass said sets of character applying controlling members and means for releasing each row of pins from a set up as determined by said selector magnets, in readiness to be again selectively acted upon by said selector magnets, said carrier and said disk being connected together in timed relation.

23. In a display device the combination with a movable display carrier, of character members separate from and adapted to be attached thereto, means for selectively bodily attaching said members to said carrier, a plurality of selector magnets for controlling said selective attaching means, a light controlled means for controlling said magnets and a movable carrier having characters thereon for varying said light controlled means for selectively controlling said magnets according to the said characters respectively.

25

AUGUST D. EITZEN.
